UNITED STATES PATENT OFFICE.

ADAM B. MOON, OF MERCER, PENNSYLVANIA.

WINDOW-VENTILATOR.

1,078,453.

Specification of Letters Patent. Patented Nov. 11, 1913.

Application filed December 4, 1912. Serial No. 734,997.

To all whom it may concern:

Be it known that I, ADAM B. MOON, a citizen of the United States, residing at Mercer, in the county of Mercer, State of Pennsylvania, have invented a new and useful Window-Ventilator, of which the following is the specification.

My invention has for its object the construction of a ventilator adapted for application to a window, and which can be readily placed in position or removed therefrom, and by means of which air may be admitted in regulated volume and free from drafts to the dwelling, car, or other structure to the windows of which my device is applied.

A further object of my invention is the construction of a device of this kind equipped with means whereby the air passing therethrough is freed from dust or other foreign substances.

With these and other objects in view my invention consists in certain constructions, combinations and arrangements of parts, the preferred embodiment of which will be hereinafter fully described in connection with the accompanying drawing and pointed out in the claims.

In the accompanying drawing wherein like parts are designated by the same reference numerals wherever they occur, Figure 1 is a perspective view of the inside of a window-frame and sash and showing my improved ventilator applied thereto; Fig. 2 is a partly broken view of the deflecting member forming the front of my device and showing a screen-frame pivoted on the inner side thereof, and Fig. 3 is a central cross sectional view.

40 4 designates a window-frame, 6 a window-sash and 7 a window-sill, all of the usual construction. The sash is shown as raised a sufficient distance to provide a space in which my improved ventilator is placed.

45 8 designates a partition board adapted to be inserted under a raised window, and which is provided at its lower and upper edges with strips 9. Between the ends of the strips 9 is an opening 10, and which is 50 covered at the rear by a downwardly-dependent hood 11 attached to the outer side of the plate 8. Secured to the lower strip 9 and extending inwardly therefrom is a bottom board 12, of a length equal to the 55 opening 10, and extending beneath said

board and secured to the inner face of said lower strip 9 is a filler piece 13, of a width adapted to rest on the top of the window-sill 7, when the device is in place.

To the plate 8, at each end of the opening 60 10 therein, are secured end pieces 14, preferably having their front edges inclined as shown. Pivoted between the said end pieces 14 is a swinging deflecting member 15 pivotally connected with the end-pieces 14 by 65 pivots 16, and carrying on its rear face a screen-frame 17 hinged thereto by suitable hinges 18. A hook 19 is provided, whereby the said screen-frame may be secured against the inner face of the deflecting member 15 or permitted to tilt therefrom, with 70 its upper edge resting against the upper strip 9.

20 designates a rack-bar connected at its rear end to the upper strip 9 of the plate 8, 75 its front end passing through an opening in the ear 21 on the upper edge of the deflecting member 15, with the teeth on the rack-bar engaging such opening, whereby the angle of the deflecting member can be 80 adjusted to regulate the quantity of air passing through the ventilator. Extending across the rear of the opening 10 is a wire-screen 22 which, in connection with the screen 17 pivoted on the rear of the deflecting member 15, serves to effectively screen 85 all dust or other foreign matter from the air passing through the ventilator. When the device is placed in a window the deflecting member 15 is tilted outwardly the desired distance and secured at such angle by the rack-bar 20. The screen-frame 17 on the rear of the deflecting member 15 is permitted 90 to swing rearwardly against the face of the upper strip 9. Air will now pass under the hood 11 and through the screen sections 22 and 17 and be deflected upwardly into the room by the deflecting member 15, thereby preventing all direct draft.

As will be seen my device is simple in construction and inexpensive in cost of construction, and will effectively serve the purpose for which it is designed.

I am aware that considerable variation is possible in the details of construction herein 105 shown and described, without departing from the spirit of my invention, and I do not intend to limit myself thereto, except as pointed out in the following claims, in which it is my intention to claim all the 110

novelty inherent in the structure shown and described as broadly as the state of the art will permit.

Having thus described my invention what I claim as new and desire to secure by Letters Patent is:

1. A ventilating device, comprising a partition board having an opening therethrough and adapted to be inserted beneath a window sash, a hood attached to the rear of said board, a screen section covering the rear of said opening, members secured to the front of said board and flanking the opening therein, a deflecting member pivotally connected between said members, and a screen member hingedly connected to the rear of said deflecting member.
- 10 2. A ventilating device, comprising a par-

tion board having an opening therethrough and adapted to be inserted beneath a window sash, a hood attached to the rear of said board, a screen section covering the rear of said opening, members secured to the front of said board and flanking the opening therein, a deflecting member pivotally connected between said members, a screen member hingedly connected to the rear of said deflecting member, and means connecting said deflecting member with said board whereby the deflecting member may be adjusted at varying angles thereto, for the purpose set forth.

ADAM B. MOON.
